UNITED STATES PATENT OFFICE

VIRGINIA C. MUSHKIN, OF BROOKLYN, NEW YORK

DESIGN FOR A CAP

Application filed July 29, 1932. Serial No. 44,475. Term of patent 3½ years.

To all whom it may concern:

Be it known that I, VIRGINIA C. MUSHKIN, a citizen of the United States of America, residing in New York city, (borough of Brooklyn) county of Kings, and State of New York, have invented a new, original, and ornamental Design for Caps, of which the following is a specification, reference being had to the accompanying drawing, forming part thereof.

The figure is a perspective view of the cap, looking at the cap from a position somewhat

above the level of the top of the cap, the design on the left of the dotted line being indicated in outline, and being a continuation of the part shown at the right of said dotted line. The parts designated by the letter A are pieces of fabric having the marginal portions doubled over on the middle portion, and gathered, as indicated at a.

I claim:

The ornamental design for a cap as shown and described.

VIRGINIA C. MUSHKIN.
